UNITED STATES PATENT OFFICE.

PERCY WILLIAM ROBERTS, OF FITZROY, NEW PLYMOUTH, NEW ZEALAND, ASSIGNOR
OF THREE-FIFTHS TO REGINALD CHARLES HENRY SANDERS AND LESLIE ALLAN
BROWN, BOTH OF NEW PLYMOUTH, NEW ZEALAND, AND ONE-TENTH TO DARCY
GLADSTONE SANDERS, OF JOHANNESBURG, TRANSVAAL, SOUTH AFRICA.

EXTENSION LADDER.

Application filed November 6, 1926, Serial No. 146,714, and in New Zealand July 14, 1926.

This invention relates to ladders of the type known as "extension ladders" wherein the ladder sections are held in their extended position by means of gravity pawls or catches 5 pivoted to the upper ladder section and adapted to engage or lock on the rungs of the lower ladder section, and wherein means such as a pulley and rope are provided for hoisting the upper ladder section on the 10 lower section.

The object of this invention is to provide improved locking means for use on ladders of the above type whereby a more positive action and greater security and rigidity is obtained when the ladder is extended. It is well known that accidents have occurred 15 through the breakage of the rung of a ladder engaged by the pawls. The present invention provides means for preventing such accidents.

According to the invention, the upper section of the ladder has secured to one side rail near its lower end, a spring actuated pawl adapted to be normally pressed outwards, and 20 engage one of the rungs of the lower ladder section to prevent sliding or collapsing of said ladder sections one upon the other.

The spring actuated pawl is connected by a link to one arm of a bell crank lever, to the 25 other arm of which is attached one end of a rope or cord which is reeved through a pulley secured to the top bar or guide of the lower ladder section.

By exerting a hoisting strain on this rope 30 or cord to raise or extend the upper ladder section on the lower section of the ladder, the bell crank lever is given turning movement and by its connecting link, causes the spring actuated pawl to be withdrawn from its operative position to permit the ladder sections 35 to be freely slid one upon the other. Immediately the hoisting strain is released on the rope or cord the spring actuated pawl is free to resume its operative position and 40 engage the nearest rung of the lower ladder section, thereby retaining the said sections in their extended positions.

A further object of the invention is to provide an improvement in the present gravity 45 hung pawls or catches, in order to provide for the moving of the latter to positions where they will not engage the rungs of the lower section of the ladder, without having to tilt

the latter, as is necessary when collapsing ladders as at present used. 55

The invention will be more particularly described with reference to the accompanying drawing wherein:—

Figure 1 is a perspective view of a portion of an extension ladder fitted with the improvements. 60

Figure 2 is a side elevation of the spring actuated pawl and means for operating the same, and

Figure 3 is a side elevation of an improved gravity operated pawl or lever. 65

The ladder comprises a lower section 1 and an upper section 2 slidably one upon the other and held together by the usual guide member 3. 70

Gravity operated pawls 4 hinged one on either side of the lower end of the upper ladder section 2 are connected together by means of a stay rod 4^a to cause them to operate together, and are adapted when the 75 ladder is raised in an inclined position, to engage the rungs of the lower ladder section 1 in the well known manner.

Secured on one rail of the upper ladder section 2 slightly above the gravity pawls 4 is a pawl 5 adapted to be normally forced or held outwards over the rungs of the ladder section 1 by means of a spring 6 acting on a bell crank lever 8. 80

This spring actuated pawl 5 is connected by a link 7 to one arm of the bell crank lever 8 the other end of the latter having attached thereto one end of a rope or cord 9 reeved through a pulley 10 secured to the upper guide member 3 on the ladder section 1. 85

By pulling on the rope or cord 9 the ladder section 2 can be slidably raised or extended on the section 1, the hoisting strain on said rope or cord 9 at the same time operating the bell crank lever 8, and through the link 7, withdrawing the pawl 5 from its position in line with the rungs of the ladder section 1. 90

On the ladder being extended to the desired length, the rope or cord 9 is slackened or released, whereupon the strain being released from the bell crank lever 8, the pawl 5 returns to its operative position under the action of the spring 6 and engages on top of the nearest rung on the ladder section 1 to prevent sliding or collapsing of the said ladder sections one upon the other. 100

The gravity operated pawls 4 at the same time engage the rung of the ladder section 1 nearest to them to provide additional support for the ladder section 2 and also to provide for additional security in case of accident to, or releasing of the spring actuated pawl 5.

One of the gravity pawls 4 is provided at its upper end with an arm 11 to which is attached 10 a rope or cord, preferably the other end of the rope or cord 9, so that when lowering the section 2, said pawls 4 can be kept clear of the rungs of the lower section 1, by maintaining a light strain on the end of the rope attached 15 to the arm 11 during the paying out of the other end of said rope or cord, the section 2 being first slightly raised on the section 1 to permit the pawls to be disengaged from the rungs with which they were engaged.

20 In the event of the breakage of the rung engaged by the pawls 4, the latter hang by gravity, so that in the descent of the section 2, the rung of the section 1 next below the broken rung is engaged by said pawls, which 25 are prevented by the casing 12 of the pawl 5,

from making complete turns on their pivots and so stop the further descent of the section 2.

What I do claim and desire to obtain by Letters Patent of the United States of America, is:

The combination with an extension ladder having extensible ladder sections, of a pair of sustaining catch devices on one ladder section adapted to engage the rungs of the other adjacent ladder section, a rope for extending said ladder sections having one end connected with one of said catch devices, said latter catch device being constructed to operate to disengage a rung of the adjacent ladder section under the hoisting strain on said rope, the other of said catch devices being connected to the other end of said rope, whereby the same may be moved from run engaging position, at will, during the hoisting move- 45

ment.

In testimony whereof I have signed my name to this specification.

PERCY WILLIAM ROBERTS.
